UNITED STATES PATENT OFFICE.

PERRY J. GARRISON, OF OXFORD, MICHIGAN, ASSIGNEE OF ONE-HALF TO WILLIAM REED, OF OXFORD, MICHIGAN.

PACKAGE-CARRIER.

1,306,849.

Specification of Letters Patent. Patented June 17, 1919.

Application filed May 9, 1918. Serial No. 283,456.

To all whom it may concern:

Be it known that I, PERRY J. GARRISON, a citizen of the United States, residing at Oxford, county of Oakland, State of Michigan, have invented a certain new and useful Improvement in Package-Carriers, and declare the following to be a full, clear, and exact description of the same, such as will enable others skilled in the art to which it pertains to make and use the same, reference being had to the accompanying drawings, which form a part of this specification.

This invention relates to package carriers, and its object is to provide a cheap and serviceable device for use on the running board of a vehicle, as an automobile or the like, by means of which a package may be quickly and securely held thereon. Another object is to provide a standard, several of which may be used depending upon the size of the package to be carried, adaptable to be clamped to the running board and having a strap and an adjustable eye adapted to occupy various positions as may be required by the size of the article to be secured thereto. A further object of the invention is to provide a standard adapted to be detachably secured to the running board of a vehicle, and having an upright or vertical arm forming a support for a package and to which it is secured by a strap of leather or webbing passing through an eye slidable longitudinally of the horizontal portion of the body. These several objects and novel features of the invention are hereinafter more fully described and claimed and shown in the accompanying drawings in which—

Figure 1 is a side elevation of my improved package carrier showing a package secured thereon.

Fig. 2 is an end elevation thereof.

Fig. 3 is an elevation of the movable eye.

Fig. 4 is a cross section taken through the body of the carrier on line $\alpha-\alpha$ of Fig. 1.

As shown in Fig. 1 the carrier consists of a body member 1, I-shaped in cross section as shown in Fig. 4, having the upper and lower flanges 2 and 3 extending on opposite sides of the body as shown. The body is preferably formed of cast aluminum but may be formed of any material either cast or forged as may be desired. The body has a terminal portion 4 bent parallel with the body 1 substantially in the form of a U, and the end thereof is provided with a threaded

aperture in which is positioned the winged bolt 5. The space between the body 1 and the leg 4 is of sufficient width to allow it to be readily inserted on a running board 6 of a vehicle as shown, and by turning the winged bolt 5 the carrier may be clamped securely to the running board and may at any time be removed therefrom as may be desired. When not required for use therefore, the standards may be removed from the running board as is desirable. The body 1 also has an upright terminal portion 7 preferably slightly tapered in form and terminating in an eye 8 in which is secured the end of a strap 9 which may be of leather or webbing. The flange 2 of the body member on the upper side thereof, as shown in Fig. 1, terminates short of the eye 8 leaving a space 10 of a thickness equal to the thickness of the body 1 between the flanges.

There is a movable eye 11 shown in detail in Fig. 3 notched on one side as indicated at 12 to engage over the flanges 2 of the body and the distance between the points 13 and 14 (which form the undercut portions of the notch 12) is slightly greater than the thickness of the body 1. This notched portion 12 is introduced onto the standard at the point 10 and is then moved downward over the flanges 2 which engage in the undercut portion of the recess 12 preventing removal of the eye from the body except at the point 10. Preferably the flanges taper toward the point 10 to allow ready insertion of the eye 11 thereon but the flange 2 may be cut away at any desired point for the purpose of insertion of the eye 11. The eye is thus movable longitudinally of the body and may occupy any position thereon as is required by the size of the article to be secured by the strap 9. The end of the strap is simply passed through the eye 11 and the end may be turned through as shown in Fig. 1 or tied in any approved manner to secure an article to the standard. Such article is indicated at 15 in cross section.

In use two of the standards are usually required to secure an article in place, but a greater number may be used as may be required by the size and character of the article to be carried, and each standard is a duplicate of the standard herein described. From the foregoing description it is evident that the standard is very simple and inexpensive in form; is readily applied to or re-

moved from a vehicle, and that an article may be very quickly and securely held in place by simply passing the strap through the running eye 11 which practically automatically 5 positions itself on the body as is required by the size of the article.

Having thus briefly described my invention, what I claim and desire to secure by Letters Patent of the United States is—

- 10 1. A package carrier for use on a running board of a vehicle comprising a standard, I shaped in cross section and having an eyed terminal portion extending at an angle to the body, the opposite end of the body being turned substantially parallel therewith in the form of a U spaced from the body to fit the running board of an automobile, a binding screw for securing the standard to the running board, the upper flange of the said body narrowing as it approaches the terminal eye of the angular portion and terminating short thereof, an eye having a notch in one side adapted to engage over the said upper flange, being insertible thereon at the 15 said eyed end of the body and being freely movable longitudinally of the body, and a strap secured to the said eyed end of the body adapted to be passed through the movable eye.
- 20 2. A package carrier for the running board of a vehicle comprising a member I shaped in cross section having one end thereof return bent to form a U to fit the running board, the opposite end being bent at a right angle to the body on the side opposite the said return bent end providing an arm positioned at the inner side of the running board, the said arm terminating in an

eye and the flange on the upper side of the body extending along the forward side of 40 the said arm and terminating short of the eye, an independent eye having a notch in one side adapted to engage over the said upper flange being insertible thereover at the said eyed end of the body and freely 45 movable longitudinally thereof, and a strap secured to the said eyed end of the body and adapted to be passed through the movable eye.

3. A package carrier for the running 50 board of a vehicle comprising a member I shaped in cross section providing oppositely disposed flanges on the upper and lower sides respectively thereof, the said member being bent at one end to form a U terminating in a threaded eye, the flange on the inside of the U fitting the running board of the vehicle, a binding screw in said threaded eye for securing the member to the running board, the opposite end of the said member 55 being bent at a right angle to the body on the side opposite the U and terminating in an eyed portion, the flange on the upper side of the body extending upward on the forward side of said eyed end and tapering to 60 a width substantially equal to the web of said member and terminating short of the eye, the said terminal eye being offset relative to the tapered flange, and a second eye having a notch on one side of a character to 65 enable the same to be inserted over the flange at the tapered end and being freely movable longitudinally of the body on the said flange.

In testimony whereof I sign this specification.

PERRY J. GARRISON.
